CLAIM

The ornamental design for a lighting signature for a headlamp of a vehicle, as shown and described.

DESCRIPTION

FIG. 1 is a front view of a lighting signature for a headlamp of a vehicle, according to the invention; and,

FIG. 2 is a side view of the lighting signature shown in FIG. 1.

The broken lines shown in the drawings represent portions of the lighting signature for a headlamp of a vehicle that form no part of the claimed design.

In the Figures, the lighting signature depicted is on the left side of the vehicle, from the perspective of the driver. The present invention also contemplates, with respect to the lighting signatures shown in these Figures, a mirror image thereof located on the right side of the vehicle.
